 graphie m. b. H., Berlin, Germany, a corpora-
 tion of Germany

Application January 28, 1936, Serial No. 61,138
 In Germany January 30, 1935

5 Claims. (Cl. 250—164)

This invention relates to an arrangement for the optic projection of an incoming television picture recreated upon the fluorescent screen of a cathode ray tube.

- 5 In the optical projection of televised pictures such as are recreated upon the fluorescent screens of cathode ray tubes, the latter in prior practice have been mostly of a kind which distinguishes itself but little so far as their construction, especially the form of the fluorescent screen, is concerned from the tubes used for the direct viewing of televised pictures recreated upon a fluorescent screen, and in this connection usually standard projector objectives of the kind generally found in the market and employed in motion-picture equipment are used. However, what has so far been left out of consideration is the fact that in the special problem involved in the projection of television pictures the curvature of 10 the fluorescent screen and the curvature of the picture field in the objective of the projector machine could be suitably so adapted to each other that advantages are realizable in reference to the cost of manufacture and the quality of 15 the recreated image upon the projection screen. The problem involved in the recreation of television pictures by optical projection differs from the problem underlying the optical projection of a motion picture or a diapositive image in 20 that the object to be imaged, that is to say, the fluorescent screen of a cathode ray tube need not be of a prefixed form, say, in the sense that a motion-picture or diapositive image must be flat, but that, inside certain limits, it is quite 25 feasible to curve the fluorescent screen of a cathode ray tube and to dimension the curvature of the image field of the projection machine objective, in such a way that practical advantages are realizable in a direction as hereinbefore indicated compared with the arrangements known in 30 the prior art.

A number of exemplified embodiments of the invention are described in what follows by reference to the annexed drawing, in which:

- 45 Fig. 1 shows one embodiment of the invention;
 Fig. 2 shows another embodiment of the invention;
 Fig. 3 shows a further embodiment of the invention;
 50 Fig. 4 is a diagram explanatory of the invention; and
 Figs. 5 and 6 are modifications of the embodiments of the invention.
 Referring to Fig. 1, 10 denotes the fluorescent 55 screen of a cathode ray tube of which, by the way,

only the truncated-cone shaped part 10 of the glass bulb 11 and the last deflection plate pair 12 is partly shown. 13 is a projection objective, and 14 is the projection surface upon which the fluorescent screen 10 is imaged. Using an ordinary projection objective, i. e. an objective which images the plane AB in the plane of the projection screen 14, it will be seen that the fluorescent screen 10 would be sharply imaged approximately upon the curved surface CD seeing that the fluorescent screen 10 itself is not in a plane. It thus follows that of a fluorescent screen which presents a convexity in the direction of the objective it will never be possible to produce a sharp image upon the projection screen 14. Hence, according to this invention, in combination with a fluorescent screen presenting a convexity towards the objective as shown in Fig. 1, an objective is to be used whose image field curvature is over-compensated (corrected). In 10 other words, such an objective would image the plane AB upon the curved surface EF and thus in turn produce from the curved object 10 a planar image upon the projection screen 14.

In the embodiment shown in Fig. 2 the fluorescent screen 10 presents a concavity towards the objective, and a projector objective is to be used which is not corrected at all, or only slightly, so far as curvature of the image field is concerned. By such an objective which offers the advantage 20 of considerably lower cost of manufacture than the standard projector objective, the curved fluorescent screen 10 will be imaged exactly in the plane of the screen 14.

In the case of the embodiment shown in Fig. 3, the fluorescent screen of the cathode ray tube is likewise curved by that directly in front of the fluorescent screen a lens 15 is mounted which presents its planar face to the fluorescent screen and its concave face to the projector objective. By the action of this lens, looking from the projection objective, the fluorescent screen will appear curved, as shall be described in more detail further below, so that in this case as well as in the embodiment shown in Fig. 3 one could speak of a curvature of the fluorescent screen. To explain the operation of lens 15, there is indicated in Fig. 4 the part of the fluorescent screen 10 (shown boxed by dotted lines), lens 15, and the ray path, drawn to an exaggerated scale. A point P of the fluorescent screen would send out light-rays L1 and L2 to the objective in the absence of the lens 15. However, by mounting the lens 15 anteriorly of the screen 10 the light-rays are refracted on passing from 40 45 50 55 60 65 70 75 80 85 90 95

glass into air in such a way that outside the glass they present a larger angle in reference to the perpendicular of incidence than inside the glass. The light-rays issuing from point P, as will thus be seen, after leaving lens 15 travel along paths as indicated by the rays L3, L4 enclosing a wider angle between each other than the light-rays L1, L2.

Extending rays L3, L4, into the lens 15, the 10 point of intersection is indicated by point P1, i.e., the point which appears to be the point P in the fluorescent screen when looking from the objective. However, the said point P1 in reference to the center of the fluorescent screen, which, 15 with the mounting of lens 15 would not appear shifted when viewed from the objective, is placed upon a surface presenting a concavity in the direction of the objective, so that for the reasons pointed out in connection with Fig. 2 it is possible to use in an arrangement as shown in Fig. 3 20 a cheap projection objective without any correction or compensation of curvature of image field.

As shown in Fig. 5 instead of a plano-concave lens similar to the lens 15 shown in Fig. 3, it would 25 be feasible also to employ a biconcave lens 16 which is also mounted at close proximity to the fluorescent screen which in this instance should present a convexity to the objective. Fig. 4 holds good also for this form of lens; and the advantage 30 of greater cheapness of the projector objective is secured in a similar way.

The lenses 15 and 16 as shown in Figs. 3 and 5 could, if preferred, be used to form the end of the cathode ray tube so that the fluorescent substance 35 would be applied directly upon the inner surface of the lens. In this case it is of great advantage to cement these lenses together with the glass wall 11 of the cathode ray tube by the use of vitreous enamel. In the part of the tube 40 being of truncated-cone shape there is provided for this end in view a flange 17 as indicated in Fig. 6 in connection with the biconcave lens. In such a combination of lens 15 or 16 and the coned

part 11 of the cathode ray tube, there is no risk of any change in the curvature of the lenses being occasioned inasmuch as vitreous enamel fuses at a lower temperature than glass and since it insures a high-vacuum-tight joint.

What we claim is:

1. In a projection system, a fluorescent screen having fluorescent material mounted on a transparent refracting support, said support having a positive radius of curvature, a bi-convex lens to produce a flat image field of the fluorescent screen, and a plane screen for receiving the produced image field. 10

2. In a projection system, a planar fluorescent screen, a plano-concave lens, means to support the lens with its plane surface upon the fluorescent screen, a plane screen in register with the lens, and a bi-convex lens interposed between said lens and screen. 15

3. In a projection system, a curved fluorescent screen, a bi-concave lens, means to support the lens adjacent to and in contact with the fluorescent screen, a bi-convex lens for producing a flat image field of the fluorescent screen, and a plane surface for receiving the produced image 20 field of the fluorescent screen. 25

4. A cathode ray tube for a projection system comprising a vitreous envelope having a surface of revolution and a flange end portion, a bi-concave lens, a layer of fluorescent material on one of the concave surfaces of the lens, and means to fasten the lens to the flange end portion of the tube with the fluorescent material immediately adjacent the tube. 30

5. A cathode ray tube for a projection system comprising a vitreous envelope having a surface of revolution and a flange end portion, a concave lens, a layer of fluorescent material on one face of said lens, and means to fasten the lens to the flange end portion of the envelope with the coated 35 surface immediately adjacent the envelope. 40
